UNITED STATES PATENT OFFICE.

ALBERT BALL, OF CLAREMONT, NEW HAMPSHIRE, ASSIGNOR TO SULLIVAN MACHINERY COMPANY, OF CLAREMONT, NEW HAMPSHIRE, A CORPORATION OF MAINE.

CHANNELING-MACHINE.

1,015,258.

Specification of Letters Patent. Patented Jan. 16, 1912.

Application filed August 25, 1906. Serial No. 332,018.

To all whom it may concern:

Be it known that I, ALBERT BALL, a citizen of the United States, residing at Claremont, in the county of Sullivan and State of New Hampshire, have invented an Improvement in Channeling-Machines, of which the following description, in connection with the accompanying drawings, is a specification, like letters on the drawings representing like parts.

My invention relates to stone working machines, being concerned more particularly with the simplification and greater efficiency of stone channeling machines.

My invention will be best understood by reference to the following description when taken in connection with the accompanying illustration of one specific embodiment thereof, while its scope will be more particularly pointed out in the appended claims.

In the drawings,—Figure 1 is a side elevation of a channeling machine standard, together with the attached reciprocating engine and cross-head, and embodying one form of my invention; Fig. 2 is a front elevation of the parts shown in Fig. 1; Fig. 3 is an enlarged detail of the mounting of the rocker reverse lever; Fig. 4 is a section on the line 4—4 of Fig. 3, and Fig. 5 is a section on an enlarged scale taken through the auxiliary cylinder head on the irregular line 5—5, Fig. 2.

Referring to the drawings and to the embodiment of my invention there illustrated, I have shown the tool standard A having an arched head a and provided with longitudinal flanged guides a', a'. The remaining parts of the channeling machine are not herein shown, their specific construction being immaterial for the purposes of the invention, but they may be of any suitable construction and the machine is here assumed to comprise an ordinary track channeler at the side of which the standard A is supported in an upright position and in a fashion well-known in the art so that the tool can cut the usual channel groove at the side of the machine as the latter is advanced along the track-way.

Slidably supported upon the guides a' of the standard are carried the engine cylinder B and the cross-head guide C, said cylinder and guide being bolted to a pair of gibbs a² (Fig. 1) which underlie the flanged portions of the guides a' and retain the cylinder

and the guide for sliding adjustment thereon as a single unit. The cylinder-guide structure is adjusted to and from the work by an adjusting screw d which is journaled in the arched head a of the frame and there held against longitudinal movement, and provided with any suitable means such as the ratchet lever d' by which the screw may be turned. This screw acts to move the cylinder and the attached guide in any suitable way, as through the medium of the fixed nut (not shown).

In constructing the standard, which, it will be observed, has two upright side members merging into the arched head and in substantially the same plane with the journal bearing for the screw (that is to say, the arched head is without substantial forward overhang), I preferably form the head integrally with the body of the standard, as by casting the same in a single piece. This I have found in practice considerably strengthens the arched head and avoids the breakage which is frequent where the arch is separately formed and then bolted to the main body portion of the standard, this having been the construction usually adopted in that type of channeler employing the non-overhanging screw support.

By the side of the engine cylinder B is located the valve chamber E provided with an interior valve (not shown) to which is imparted a reciprocatory movement through the valve rod e actuated through connections to the cross-head F, the latter being suitably mounted for sliding movement upon the sliding cross-head guide C. The valve referred to acts to control reversal of the main valve of the engine although its particular purpose and construction are not material to the object of the invention herein set forth.

Reciprocatory movement is imparted to the valve stem e through its jointed connection at e' to the rocker reverse lever e², near the fulcrum e³ of the said lever; the free end of the lever being jointed to a link e⁴ pivotally connected to the cross-head at e⁵.

In channeling machines of this type it has heretofore been usual to mount or pivot the valve-actuating rocker lever e² upon a support attached to the lower part of the cylinder head, such support thereby considerably obstructing the space below the cylinder head and preventing easy access

to the packing gland *b*. In the present construction I have materially simplified the mechanism by providing a boss or fulcrum support *e*⁶ at the side of the sliding cylinder-guide structure and herein, although not necessarily, at the side of the cross-head guide itself. This removes the usual obstruction, heretofore necessitated by the pivotal mounting of the rocker reverse lever, 5 from the space beneath the cylinder head and about the stuffing box gland *b*.

Referring more particularly to Figs. 1, 2 and 5, the piston at its upper end is provided with a tail-rod *g* (see Fig. 5) which 15 projects through the upper end of the cylinder and is slidably mounted in a sleeve or bushing *h*, the latter having a tapered seat in the auxiliary cylinder head *H*. The bushing *h* is held to its seat, and the open 20 end of the auxiliary head closed, by means of the plug *h'* threaded into the top of the auxiliary head. In addition to the guidance which is afforded by the presence of the auxiliary head *H* serving to maintain 25 the alinement of the piston and cross-head, the said auxiliary head also provides means for lubricating the tail-rod and thereby supplying lubricant to the engine cylinder. For this purpose there is formed in the auxiliary 30 head a hollow chamber *h*², which, being separated from the tail-rod by the bushing *h*, forms an annular reservoir for the lubricant. This reservoir may be filled or replenished through the passage *h*³ arranged in an offset portion of the head and 35 closed by the plug *h*⁴.

Leading from the lower end of the reservoir is the lateral exit passage *h*⁵ (see Fig. 5) having connection through the valved 40 passage *h*⁶ with an annular groove *h*⁷ located opposite a series of apertures in the bushing which serve to conduct the lubricant to the surface of the tail-rod. The passage *h*⁶ is normally closed by the ball 45 valve *h*⁸, the latter, however, being raised by superior pressure from beneath to permit the oil to pass to the tail-rod. Pressure is admitted intermittently at each forward stroke of the piston from the head end 50 of the cylinder to the pressure chamber *h*⁹ at the end of the tail-rod through a vertical passage (shown in dotted lines Figs. 1 and 5) formed in an offset portion *h*¹⁰ of the head and directly connecting the cylinder 55 and the chamber *h*⁹. When pressure is thus admitted it enters the groove *h*⁷ and lifts the ball valve *h*⁸ to the space allowed for ball movement by the adjusting screw *h*¹¹ (Fig. 5). When the ball is lifted oil passes 60 to and within the bushing *h* and by reciprocation of the tailrod is carried to the cylinder, oiling the parts gradually as required. By adjusting the screw *h*¹¹ the lift of the ball and the feed of the oil may be regulated 65 as desired.

While I have shown and described one form of my invention for the purpose of illustrating the parts thereof, it is to be understood that extensive departures may be made from the details of the described form without departing from the spirit 70 thereof.

Claims—

1. A channeling machine comprising, in combination, a channeling tool carrying member; a cylinder and piston to actuate the same; valve means to govern the cylinder; valve controlling connections between the tool carrying member and the valve means; a tail rod to guide the piston and tool; an auxiliary cylinder head to receive the tail rod; a lubricating chamber in the auxiliary head; and means to regulate the flow of lubricant to the tail rod, the whole being arranged to facilitate the guiding of the piston and tool and thereby to insure the proper control of the cylinder governing valve through its connections with the tool. 75

2. A channeling machine comprising, in combination, a channeling tool carrying member; a cylinder and piston to actuate the same; an auxiliary cylinder head having a lubricant chamber; a tail rod extending into the auxiliary cylinder head and receiving lubricant from said chamber; and means to regulate the flow of lubricant to the tail rod. 80

3. A channeling machine comprising, in combination, a channeling tool carrying member; a cylinder and piston to actuate the same; a tail rod to guide the piston and tool carrying member; an auxiliary cylinder head; a bushing in said head in which the tail rod is mounted; a lubricant chamber around said bushing; lubricating passages leading from the chamber to the tail rod; an adjustable valve controlling said passages; and provision for controlling the operation of the auxiliary cylinder head and lubricating means, by movement of the channeling tool. 100

4. A channeling machine comprising, in combination, a channeling tool carrying member; an actuating cylinder and piston for the same; a lubricant reservoir associated with said cylinder; lubricant feeding passages leading from said reservoir; a pressure-governed check valve controlling said passages; and means to control the pressure governing said valve, said means being connected to and controlled by the piston in its movement. 105

5. A channeling machine comprising, in combination, a channeling tool carrying member; an actuating cylinder and piston for the same; a tail rod attached to the piston; an auxiliary cylinder head; a bushing therein in which the tail rod is mounted; a lubricant chamber around said bushing; 110

lubricating passages leading from the chamber to the tail rod; an adjustable ball valve controlling said passages; a pressure passage connecting the cylinder with the interior of said bushing; a cylinder valve controlling the pressure in the cylinder and the pressure within said bushing; and operating means for the cylinder valve controlled by movement of the piston, said means being offset 10 from in front of the cylinder to leave the head of the latter unobstructed.

6. A channeling machine comprising, in combination, a channeling tool carrying member; an actuating cylinder and piston 15 for the same; a head closing the end of the cylinder having a lubricant reservoir; lubricant passages leading from said reservoir to convey lubricant to the cylinder; a pressure-governed check valve controlling said

passages; and piston-governed pressure controlling means to synchronize the operation of the check valve and the motion of the piston.

7. A channeling machine comprising, in combination, a channeling tool carrying member; an actuating cylinder and piston for the same; pressure controlled lubricating means for the cylinder; and piston controlled means to govern the pressure, to synchronize the operation of the lubricating means and the movement of the piston.

In testimony whereof, I have signed my name to this specification, in the presence of two subscribing witnesses.

ALBERT BALL.
